United States Patent Office.

THEOPHILUS WEAVER, OF HARRISBURG, PENNSYLVANIA, ASSIGNOR TO
J. W. MOFFITT, OF SAME PLACE.

Letters Patent No. 96,175, dated October 26, 1869.

IMPROVEMENT IN COMBINED LATCH AND LOCK.

The Schedule referred to in these Letters Patent and making part of the same.

To all whom it may concern:

Be it known that I, THEOPHILUS WEAVER, of the city of Harrisburg, county of Dauphin, and State of Pennsylvania, have invented a new and useful Improvement on a Latch-Lock; and I do hereby declare that the following is a full, clear, and exact description of the construction and operation of the same, reference being had to the annexed drawings, making a part of this specification, in which—

Figure 1 is a plan of the lock unlocked, and as a knob-latch.

Figure 2 is a plan of the lock locked.

Figures 3, 4, and 5 are views of the sectional keeper. Figure 6 is a plan of the knob and key-escutcheon. Figure 7 is a side view of the knob-spindle.

The nature of my improved lock is such as to constitute it a cheap, simple, and efficient indoor-lock for cupboards, clothes-presses, cases, window-sash, &c., whose bolt is a lock-bolt or latch at pleasure.

It consists chiefly of a swinging-lever, and a traversing spring-retaining yoke, arranged for knob-attachment in a suitable case.

The swinging-lever A B D, figs. 1 and 2, has trunnions at M, which have bearings in the shells of the case, a short arm, O, notched to receive loosely the actuating tooth 1 of arbor Z, and a long looped arm, B F, which has a bolt-head, A, for engaging with the keeper outside of the case edge.

Said head is surmounted by a crown-piece, H', which closes the passage in the case-wall necessary for the clearance of it, when it is vibrated in latching.

Said bolt-head A is located in a projected nosing of the case, and this is so made to bring or keep the knob and key at a proper distance from the door-edge without enlarging the whole lock-body.

The arm of said lever from A to M takes the inside line of the said nosing.

Said long looped arm retreats from bolt-head A toward the centre of the lock-case, where it forms an abrupt detour at B, leaving a space between shoulder B and the central screw-post C D, sufficiently large for clearance of said shoulder B, when the lever is vibrated in latching.

Said arm returns, at the rear of post C D, to its main line, to form a spiral spring-support, a, of as great throw as possible between it and the foot of the traversing yoke, which supports the other end of the spring, and in such relative direction are said supports placed that said spring may be as near as possible in the chord-line E S w of the arc, which the arm-end E describes.

Said long arm is stopped both ways by post C D in the loop between B and F.

The traversing spring-retaining yoke has a rectangular locking-head, L, figs. 1 and 2, on a bar, which terminates in two curved arms N and Y on opposite

sides of it, the former serving as a key-lift, the latter as a spring-carrier.

Said head L is made to fill the space between the bolt-shoulder B and the post C D, as shown in fig. 2, when the lock is locked; and it has a tooth, V, at its lower rear end, which rests in a notch on the crown of post C D, when the lock is unlocked or acts as a knob-latch, as shown in fig. 1.

Said head L is so formed on the end of its bar as to enter into its place in locking like a slightly-tapering wedge, and to fall sufficiently deep to make the locked position secure and rattle-proof.

The curved arm N is so formed that the key-bit will play freely between N and L without requiring it to be returned after it has locked or unlocked the lock, to remove it from the lock, while at the same time it has an inside ledge, 3, so near the key-hole K that the key-bit acts on it in lifting and carrying the yoke from the locked to the unlocked position, and vice versa, as shown in figs. 1 and 2.

The spring-carrier arm Y has a foot, on which is a pin, w, for the support of the spiral spring S in such relative direction as to clear arbor Z, to keep in the chord-line E S w, as described, and to poised the yoke when it is lifted with the key-bit at 3.

The yoke is styled traversing, because it is neither pivoted nor fixed as tumblers are, but it swings and walks when acted upon by the key-bit, the spring, and the knob.

When the lock is unlocked, the yoke is kept poised on post C D, by the tension of the spring, and when locked is kept locked by the same tension. The lock, therefore, can be applied in a direct or inverted position, and thus serve as a right or left-hand lock. The bolt-head, however, may be made Janus-faced, and thus obviate the necessity of inverting the lock.

The pins g and h, in the case, are employed merely to limit the throw of the yoke.

For cupboard or other side-door use, the bolt-keeper for this lock is made adjustable to different thicknesses of doors, as the bolt-head must be kept on the inside of the jamb, that is, on the plane of the inside of the door, when it is closed.

It consists of two sliding dovetailed plates, as shown, separated in figs. 3 and 4, and combined in fig. 5.

The plate in fig. 3 is formed with a ledge or tread, r, on its three sides, and has two screw-seats 4 and 5, near the end ledges, and a little out of the middle toward the unledged side.

The blade or plate, fig. 4, fits loosely into recess of plate, fig. 3, and has its sides cut at 6, to pass the screws in the other plate, while two lugs, 7, serve to stop plate, fig. 4, when it is slid out full length required, the latter also having a strong ledge, 8, to strengthen the nip for the bolt.

The two plates are applied, as shown in fig. 5.

Plate H is under and is clamped against the jamb by the screws in the other plate.

The knob and key-escutcheon are cast in one piece, as shown in fig. 6. The knob-cavity floor has a slot, P¹, in it, for the insertion of the lug P² on the spindle, shown in fig. 7. Said lug is cast on spindle A², and thus obviates the necessity of drilling a hole and plugging it, as is usually done.

The escutcheon is first mounted in place on a door and the knob and spindle inserted. The spindle is then half revolved, and the lock is attached on the inside of the door.

If the lock is now fastened in position, the spindle cannot be detached and will adjust itself to different thicknesses of doors.

The object of this lock is mainly to furnish a combined latch and lock for cupboard and clothes-press use, but it can also be modelled to make it a general builders' lock.

The latches and locks in the market are not complete for inside-door use, and there is therefore a want

felt for a medium-sized lock between door-locks and chest, or till-locks, which must be a latch with a good knob, or a knob-lock with key, at the pleasure of the operator.

I claim—

1. The traversing spring-retaining yoke L N Y, when made to operate substantially in the manner as and for the purpose herein set forth.

2. In the swinging-lever A M, the loop B F, pin a, and notch O, all arranged as and for the purpose specified.

3. The combination of yoke L N Y with lever-arm A B F, when arranged to support the spring in the chord-line E S w.

4. The adjustable keeper, consisting of the plates H and I, constructed and arranged as herein set forth.

THEOPHILUS WEAVER.
